UNITED STATES PATENT OFFICE.

SETH A. CRONE, OF NEW YORK, N. Y.

BRAKE-BEAM FOR RAILWAY-CARS.

No. 832,598.

Specification of Letters Patent.

Patented Oct. 9, 1906.

Application filed April 14, 1906. Serial No. 311,643.

To all whom it may concern:

Be it known that I, SETH A. CRONE, a citizen of the United States, and a resident of New York city, in the county of New York 5 and State of New York, have invented certain new and useful Improvements in Brake-Beams for Railway-Cars, of which the following is a specification.

The invention relates to improvements in 10 brake-beams for railway-cars; and it consists in the novel features and construction herein-after described, and particularly pointed out in the claims.

Brake-beams of the class to which my invention 15 pertains comprise a rolled body-beam of suitable length, brake-heads of suitable construction on the ends thereof, and a fulcrum for the brake-lever; and my invention has for its object to produce a novel fulcrum for use in such beams, said fulcrum being efficient and capable of being firmly and quickly applied to the beam.

My present invention pertains more especially to improvements in the class of brake-beam fulcrums described and claimed in Letters Patent of the United States numbered, respectively, 720, 676, dated February 17, 1903, and 731,668 granted June 23, 1903; and its object is to produce a novel forged-metal 30 fulcrum having its parts bent into the required shape, the parts of the fulcrum while being given such shape not being materially stretched or weakened, my invention contemplating the manufacture of the fulcrum in 35 two separate parts without during the bending operations stretching or in any other manner weakening or unduly punishing the same.

The invention will be fully understood 40 from the detailed description hereinafter presented, reference being had to the accompanying drawings, in which—

Figure 1 is a detached top view of a fulcrum constructed in accordance with and 45 embodying the invention, the two parts of the fulcrum being shown in the position they occupy when upon a brake-beam. Fig. 2 is a detached top view of the inner or beam member of the fulcrum, Fig. 2 corresponding with 50 Fig. 1 with the jaw member of the fulcrum removed. Fig. 3 is a detached top view of the jaw member of the fulcrum. Fig. 4 is an outer end view of the complete fulcrum, taken 55 from the right-hand end of Fig. 1. Fig. 5 is an enlarged sectional view on the dotted line 55 of Fig. 4 through the base portion of the

beam member of the fulcrum and is presented to illustrate the seat formed therein to receive the inner portion of the jaw member of the fulcrum. Fig. 6 is a transverse section 60 through a brake-beam having the fulcrum applied thereto, the fulcrum being shown in side elevation; and Fig. 7 is a detached inner end view of the beam member of the fulcrum.

In the drawings, 10 designates a portion of 65 the usual body-beam, and 11 the novel fulcrum of my invention, which is applied centrally on one edge of the beam and comprises a beam member 12 and lever or jaw member 14, each being in one integral piece of forged 70 metal folded at about its middle portion, and the two members being brought or hooked together at such folded portions thereof, so that the sides of the beam member project in one direction to engage the body-beam and the 75 sides of the lever or jaw member project in the opposite direction to receive between them the usual brake-lever, (not shown,) said lever being usually mounted upon a pin extended through apertures 15 in the sides 16 80 17 of said member 14.

The member 12 is formed from an initially-straight bar of forged metal, said bar being bent and folded to form a diagonally-disposed loop comprising a central straight section 18 85 and side sections or members 19, the said straight section 18 being extended on a diagonal line, Fig. 7, with respect to the beam 10 and said side sections or members 19 comprising flanges 20 21, adapted to closely engage the body-beam 10 and formed by the end portions of the bar being bent inwardly 90 from the opposite ends of the diagonal section 18 on lines parallel with the longitudinal edges of said beam, whereby the flanges 21 become parallel with the faces of the web of 95 the body-beam and are carried in a direction from and out of transverse alinement with each other, which is one of the results accomplished by my invention.

The formation of the beam member 12 in the manner shown and described is advantageous because of the separation of the flanges 21 from transverse alinement with each other, whereby two rivets are required for fastening said member to the 100 body-beam, and also from the fact that the flanges 20 21 are conveniently produced without unduly stretching or weakening the metal, which is one of the prime objects accomplished by my invention. I preferably form 105 in the diagonal section 18 a seat 22 to receive the inner end of the jaw member 14, this seat 110

22 being simply a recess pressed into and extending transversely of said section 18 and forming edge shoulders 23, Fig. 5, adapted to engage the edges 24, Fig. 3, of said jaw member 14.

5 The jaw member 14 is formed from an initially-straight bar of forged metal folded at about its middle portions to form a straight section 25 and side members or sections 16 10 17, the latter being diagonally disposed with respect to the body-beam and at their outer ends being sufficiently separated from each other to properly receive between them the brake-lever. The section 25 of the member 15 14 is long enough to straddle the diagonal section 18 of the member 12, and from its end edges the sides 16 17 bow inwardly toward each other for a certain distance and then extend on parallel lines, as shown in 20 Fig. 3. It will be observed that the jaw member 14 is formed to afford the angularly-disposed sides 16 17 without previously offsetting the bar and by simple bending operations not calculated to unduly weaken or 25 stretch the metal, the section 25 being straight and the sides 16 17 being parallel with the end edges of said section 25, as the dotted lines in Fig. 4 indicate.

30 The members 12 14 are hooked one upon the other, as shown in Fig. 1, and the member 12 applied and secured to the body-beam 10 by rivets extending through the web thereof and the flanges 21 of the member 12, whereby member 12 is enabled to bind the 35 jaw member 14 in position, the section 25 of said jaw member being confined between the flange of the body-beam and the diagonal section 18 of the member 12, with its edges 24 in engagement with and confined between 40 the shoulders 23 of the seat or recess 22. In instances where the same may be deemed expedient or desirable the sections 18 25 of the members 12 14 may be welded together or 45 secured together by rivets passing through them, whereby the due relation of the members 12 14 with each other may be maintained. The seat or recess 22 is adapted and 50 intended to maintain the due relation of the member 14 to the member 12—that is, to prevent any turning or swiveling of the member 14 when in use; but if it is not desired to employ the seat or recess 22 the two members comprising the fulcrum may, as above explained, be welded or riveted together or 55 otherwise arranged, as may be preferred. Initially the fulcrum is in two parts, each 60 separately formed from a plain straight bar without upsetting the bar at its ends and without unduly stretching the metal in the bending operations.

In prior patents showing forged-metal fulcrums formed from bars the body-beam flanges have been parallel, or nearly so, with each other, considered transversely on vertical lines through the body-beam, and this

has resulted in two features, the first being that a single rivet is used to secure the fulcrum to the beam, whereby the tendency of the fulcrum to swivel on the rivet is not effectually overcome, and the second being 70 that the inner end portions of the bar or bars are carried so abruptly inwardly from the diagonal sides for the brake-lever toward a longitudinal center line through the fulcrum that the metal becomes stretched on diagonally opposite edges or that the operation of offsetting the inner ends of the bar or bars in opposite directions, as shown in the aforesaid Patent No. 731,668, must be resorted to to prevent that result. In accordance with 80 my present invention I form the fulcrum of two independent plain bars of forged metal and secure the fulcrum to the beam by two independent separated rivets, and I avoid both undue stretch of the metal and the necessity of offsetting the bars. 85

What I claim as my invention, and desire to secure by Letters Patent, is—

1. A brake-beam fulcrum of forged metal comprising angularly-disposed sides apertured to receive the brake-lever pin, and a beam member supporting said sides and comprising the diagonally-disposed section from whose ends the end portions of the bar are bent inwardly on lines parallel with the edges 95 of the beam to form the beam-flanges, whereby said flanges become spread apart; substantially as set forth.

2. A brake-beam fulcrum of forged metal comprising the angularly-disposed jaw member and the beam member separately formed from integral bars folded at their middle portions and at said portions brought together on lines crossing each other, said jaw member comprising the middle section 25 and sides 16, 17, and said beam member comprising the diagonally-disposed section from whose ends the end portions of the bar are bent inwardly on lines parallel with the edges of the beam to form the beam-flanges, whereby said flanges become spread apart; substantially as set forth. 105 110

3. A brake-beam fulcrum of forged metal comprising the angularly-disposed jaw member and the beam member separately formed 115 from integral bars folded at their middle portions and at said portions brought together on lines crossing each other, said jaw member comprising the middle section 25 and sides 16, 17 which extend inwardly toward 120 each other adjacent to said section and then continue on parallel lines to receive between them the brake-lever, and said beam member comprising the diagonally-disposed section from whose ends the end portions of the bar are bent inwardly on lines parallel with the edges of the beam to form the beam-flanges, whereby said flanges become spread apart; substantially as set forth. 125

4. A brake-beam fulcrum of forged metal 130

comprising the angularly-disposed jaw member and the beam member separately formed from integral bars folded at their middle portions and at said portions brought together 5 on lines crossing each other, said jaw member comprising the middle section 25 and sides 16, 17, and said beam member comprising the diagonally-disposed section recessed to engage opposite edges of said section 25 10 and from whose ends the end portions of the bar are bent inwardly on lines parallel with

the edges of the beam to form the beam-flanges, whereby said flanges become spread apart; substantially as set forth.

Signed at New York city, in the county of 15 New York and State of New York, this 11th day of April, A. D. 1906.

SETH A. CRONE.
